UNITED STATES PATENT OFFICE

2,386,480

TYPEWRITING MACHINE

William H. Kupper, Hartford, Conn., assignor to
 Royal Typewriter Company, Inc., New York,
 N. Y., a corporation of New York

Application March 8, 1944, Serial No. 525,587

2 Claims. (Cl. 197—179)

This invention relates to typewriting machines and more particularly to mechanism for changing the positions or settings of tabular stop elements.

In accordance with the invention, mechanism for resetting tabular stops includes a resetting bar of preferably light construction and which is mounted by novel means so as to be held against lateral deflection when operated to reset a plurality of tabular stops from their operative 10 positions to their inoperative positions.

An object of the invention is to provide tabular stop resetting mechanism including a bar or like resetting element extending adjacent a plurality of aligned tabular stops and being engageable with the stops for simultaneously moving them to inoperative positions, the resetting bar having bearing contact with a relatively fixed support in an intermediate zone as well as at its ends so as to be supported against lateral deflection.

Another object of the invention is to provide stop resetting mechanism of the character stated in which the resetting bar has rotatable bearing contact with the support, so as to be, in effect, journaled on said support substantially throughout the length of the bar.

A further object of the invention is to provide resetting mechanism of the kind referred to in connection with mechanism for setting tabular stops individually in operative position, and for moving the stops individually back to inoperative position. Other objects of the invention will become apparent from a reading of the following detailed description, the appended claims, and the accompanying drawing, in which:

Figure 1 is a fragmentary vertical sectional view fore and aft of a typewriter equipped with mechanism embodying the invention and showing stop setting and resetting mechanism in their neutral or inactive conditions;

Figure 2 is a fragmentary vertical sectional view on an enlarged scale and showing a tabular stop being set into operative position by a stop setting finger;

Figure 3 is a view similar to Figure 2 but showing a stop resetter bar in operated position after having returned a plurality of tabular stops to inactive positions;

Figure 4 is a fragmentary detail longitudinal section on the line 4—4 of Figure 1 and drawn on an enlarged scale;

Figure 5 is a fragmentary perspective view showing the stop resetter bar and parts of a tab-

ular stop mounting frame separated from each other;

Figure 6 is a detail perspective view of a lever for operating individual stop resetting mechanism;

Figure 7 is a detail view partly in elevation and partly in vertical section showing a stop setting push rod and its mounting; and

Figure 8 is a fragmentary section on the line 8—8 of Figure 1 drawn on a reduced scale.

Mechanism constructed in accordance with the invention may be embodied in various kinds of typewriter or like machines. The drawing shows a preferred embodiment in association with conventional typewriter parts similar to those included in the Royal Standard typewriter, the basic construction of which is well known. The conventional parts illustrated include a main frame element A on which a carriage element B is mounted for letter spacing and return movements by conventional means, not shown. The carriage includes end plates 1 and 2 on which a tabular stop frame assembly C is mounted to extend longitudinally or in the direction of carriage travel. The stop frame C is similar in construction to the stop frame shown in United States Patent to Myers et al. No. 1,892,071, granted December 27, 1932. The frame includes upper and lower rack bar members 3 and 4 respectively formed with angular end pad portions 5—5 extending into openings 6—6 in end brackets 6a—6a, screws 7 extending through the brackets 6a and into the rack bars for holding the parts assembled. Each bracket 6a is provided with a stud 8 which extends through the adjacent carriage end plate and is locked in place by nuts 9.

The upper rack bar 3 is curved along its top edge but has flat sides and a flat bottom, the lower rack bar 4 being rectangular. The bottom of the upper rack bar 3 and the top of the lower rack bar 4 are formed respectively with grooves 10 and 11 which register with each other and which are spaced longitudinally of the rack bars at letter space intervals.

Mounted on the tabular stop frame C is a plurality of laterally settable tabular stops, two of which are shown at D and D'. The tabular stops are similar to individual tabular stops disclosed in the Myers et al. Patent No. 1,892,071 and include a bridge or central portion 12, upper legs 13 and 14 which project alongside opposite sides of the upper rack bar 3, and lower lugs 15 and 16 which project downwardly alongside opposite sides of the bottom rack bar 4. Each tabular stop is provided with a spring 17 mounted

on a pin 18 to have one end hooked at 19 around the edge of the tabular stop just above the lug 16, the other end of the spring being curved as at 20 so as to press against the top rack bar 3. The arrangement is such that each tabular stop D can be shifted transversely of the frame C to an operative position shown in Figure 2 or to an inoperative position shown in Figure 3, the spring 17 frictionally and yieldably maintaining the stop in whichever position it has been set.

When a tabular stop is set in its operative position as shown in Figure 2, its rear edge projects toward the back of the machine sufficiently to be engaged by a stop device comprising a tabular finger 21 when the latter is moved from its inoperative position shown in Figure 1 to the operative position shown in dotted lines in Figure 2. Only a portion of the tabular finger 21 is shown, but its construction and mounting on the machine frame is well known and is illustrated for example in the Myers et al. Patent No. 1,892,071.

The tabular stops D may be set in operative position by mechanism similar to that disclosed in the Myers et al. patent referred to above. A push rod 22 equipped with a finger key end 23 is mounted to slide in a guide opening 24 in a cross bar 25 forming part of or being fixed with respect to the frame A. A screw 26 extending through the top of the cross bar and being locked in position by a lock nut 27, has its lower end provided with a pin 28 received in a slot 29 in the push rod 22. The pin 28 cooperates with the end walls of the slot 29 for limiting reciprocation of the push rod 22. The rear end of the rod 22 projects through an opening 30 in an ear 31 turned over at one end of an arm 32 of a bell crank lever 33 pivoted on the frame A as at 34. The other arm 35 of the lever 33 is formed with a bifurcated end 36 which straddles the reduced end 37 of a lever 37^a pivoted on the frame A as at 38. The other end of the lever 37^a is pivoted as at 39 to a link 40 which extends upwardly and is pivoted as at 41 to a stop setting lever 42, itself pivoted on the frame as at 43. The lever 42 includes an upper arm or finger 44 which is adapted to be rocked rearwardly to engage the lug 16 of a juxtaposed stop D for shifting the stop from the position shown in Figures 1 and 3 to the position shown in Figure 2. A spring 45 interposed between a projection 46 on the lever 42 and an anchoring screw 47 urges the lever 42 to rock to the inactive position shown in Figure 1. A lower projection 48 on the lever 42 acts as a stop engageable with the frame A for limiting rocking of the lever 42 by the spring 45.

In operation, when it is desired to set any given tabular stop D to its active position, the carriage is moved until that particular stop is immediately behind the finger 44 of the stop setting lever 42. Then the push rod 22 is pushed rearwardly to rock the lever 33 counterclockwise, rock the lever 37^a clockwise, as viewed in Figure 8, and rock the stop setting lever 42 counterclockwise as viewed in Figure 1, thereby causing the finger 44 to engage the lug 16 of the juxtaposed stop and move the latter to its operative position.

Means are provided for resetting any individual stop D from its operative position to its inoperative position. A push rod 49 equipped with a key end 50 is mounted to slide in a guide opening 51 in the cross bar 25. A screw 52 extending through the top of the cross bar and being held against turning by a lock nut 53 has its

lower end formed as a pin 54 projecting into a slot 55 in the rod 49. The pin 54 cooperates with the end walls of the slot 55 for limiting to and fro movement of the push rod 49. The rear end of the push rod 49 engages an ear 56 formed on one arm 57 of a bell crank lever 58 pivoted on the cross bar 25 as at 59. The other arm 60 of the lever 58 is connected to a link 61, the rear end of which is connected to an arm 62 on a bell crank lever 63 pivoted on the main frame as at 64. The other arm 65 of the lever 63 is connected by a link 66 to one arm 67 of a lever 68 pivoted as at 69. The other arm 70 of the lever 68 is offset rearwardly to extend under an arm 71 of a lever 72 pivoted as at 73. The other arm 74 of the lever 72 engages a downwardly extending finger 75 on a rock frame 76 pivotally mounted as at 77. A shouldered stud 78 journals a roller 79 on the rock frame 76. A spring 80 interposed between an ear 81 on the rock frame 76 and a fixed ear 82 urges the rock frame to its inoperative position wherein the roller 79 is disposed to the rear of any stop D set in operative position.

When it is desired to reset an individual stop D in its inoperative position, the carriage is moved so as to position that particular stop directly in front of the roller 79. Then the push rod 49 is pushed rearwardly so as to rock the lever 58, move the link 61 forwardly, rock the lever 63, pull down on the link 66, and rock the lever 68, in turn to rock the lever 72 counterclockwise as viewed in Figure 1. This will move the finger 75 rearwardly so as to rock the frame 76 and move the roller 79 forwardly and against the stop D which is then pushed forwardly to its inoperative position.

In accordance with the invention, means of novel and improved construction are provided for simultaneously moving to their inoperative positions all tabular stops D which have been set in their operative positions. The resetting means includes a universal resetting bar which is light but is so mounted that it cannot be deflected laterally even when it is operated to reset simultaneously a large number of tabular stops D. In the form shown the rack bar 4 has its front vertical side or face longitudinally grooved as at 83 with the wall of the groove being cylindrical or concave. A rockable universal resetter bar 84 extends along in the groove 83 and is provided at its opposite ends with pin ends 85 and 86 respectively journalled in bearings 87 and 88 formed on the end brackets 6^a. The resetter rod 84 has a convex surface 89 curved to match the curvature of the grooved wall 83 so that the bar surface 89 has bearing contact or engagement with the groove wall substantially throughout the length of the bar 84. A lip part or edge 84^a on the bar 84 is adapted to engage the lugs 16 of stops D in operative position so that upon rocking of the bar 84 clockwise as viewed in Figures 1, 2, and 3, the edge 84^a will push all of the engaged lugs 16 forwardly to shift the associated stops D to their inactive positions.

The resetter bar 84 is sector shaped in cross section and its longitudinally extending convex outer surface portion 89 is segmental and extends only partially around the axis of the bar. The bar 84 is undercut as at 84^b (see Figures 2 and 3) to provide a longitudinally extending depression which forms the resultant lip 84^a. This construction provides maximum stiffness and operating stability of the resetting mechanism with a minimum weight of the parts.

Means for rocking the resetter bar 84 includes an arm 90 extending down from one end of the bar and being provided with an extension 91 connected to one end of a spring 92, the other end of which is anchored on a cover strip 93 secured to the top rack bar 3 by screws 94, the arrangement being such that the spring 92 urges the resetter bar 84 to its inactive position shown in Figures 1 and 2. For moving the resetter bar to its active position shown in Figure 3, a finger lever 95 is pivoted on the top rack bar 3 as at 96 and is provided with a downwardly extending projection 97 engaging the arm 90 on the resetter bar 84.

In operation, to reset a plurality of tabular stops D simultaneously from their operative positions shown in Figure 2 to their inoperative positions shown in Figure 3, the finger lever 95 is depressed so as to rock the resetter bar 84 clockwise from its Figure 2 position to its Figure 3 position. The bar edge 84^a will engage and move the lower lugs 16 of all of the stops D to be reset thereby shifting the stops to their inoperative positions. It will be apparent that when a large number of tabular stops are to be reset a considerable force must be exerted on the stops considered collectively in order to overcome the total frictional resistance due to the holding action of the several springs 17. This quite large operating force reacts transversely against the resetter bar 84 and tends to deflect it laterally. However, the bearing contact of the groove wall 83 with the rod surface 89 substantially throughout the length of the rod, that is in an intermediate zone as well as at its ends, prevents deflection of the rod even though the latter is light and of quite small section.

The construction disclosed by way of example embodies the invention in a preferred form, but it will be apparent that changes may be made and without departing from the invention as defined in the claims.

I claim:

1. In a tabulating mechanism for typewriting machines, a stop frame comprising upper and lower rack bars respectively provided on their lower and upper faces respectively with transverse grooves spaced apart at letter space intervals; a plurality of tabular stops mounted in each pair of upper and lower grooves and being shiftable from inoperative to operative positions and vice versa, each stop comprising spaced lugs embracing one of said rack bars for limiting shifting of said stop; a longitudinally extending

groove in said one of said rack bars having a concave wall; and a universal stop resetter bar rockable for shifting tabular stops from operative to inoperative position, said resetter bar being sector shaped in cross section and having a longitudinally extending convex segmental outer surface portion in bearing engagement with said groove wall, said resetter bar being undercut to provide a longitudinally extending depression which receives the lugs of tabular stops which are in operative positions, said undercut forming a resultant lip at said surface portion engageable with the lugs of tabular stops which are in operative positions for moving said tabular stops to inoperative positions upon rocking of said resetter bar.

2. In tabulating mechanism for a typewriter or like machine including a frame and a carriage movable thereon for tabulating operations, a stop frame comprising upper and lower rack bars mounted on said carriage and being provided on their lower and upper faces respectively with transverse grooves spaced apart at letter space intervals; a plurality of tabular stops mounted in each pair of upper and lower grooves and being shiftable transversely of said bars from inoperative to operative positions and vice versa, each stop comprising spaced lugs embracing the lower rack bar for limiting shifting of said stop; a stop device mounted on said frame for cooperation with a tabular stop set in operative position; means mounted on said frame for engaging and moving a selected tabular stop from inoperative to operative position; means mounted on said frame for engaging and moving a stop from operative to inoperative position; a longitudinally extending groove in said lower rack bar having a concave wall; and a rockable universal stop resetter bar journaled on said carriage, said resetter bar being sector shaped in cross section and having a longitudinally extending convex segmental outer surface portion in bearing engagement with said groove wall, said resetter bar being undercut to provide a longitudinally extending depression which receives the lugs of tabular stops which are in operative positions, said undercut forming a resultant lip at said surface portion engageable with the lugs of tabular stops which are in operative positions for moving said tabular stops to inoperative positions upon rocking of said resetter bar for shifting said tabular stops to inoperative position upon rocking of said resetter bar.

WILLIAM H. KUPPER.
